UNITED STATES PATENT OFFICE

97,527

DESIGN FOR A TEXTILE FABRIC

Eugene Irving Hanson, New York, N. Y.

Application August 9, 1935, Serial No. 58,030

Term of patent 3½ years

To whom it may concern:

Be it known that I, Eugene Irving Hanson, a citizen of the United States of America, residing in Borough of Manhattan, city, county, and State of New York, have invented a new, original, and ornamental Design for a Textile Fabric, for which the following is a specification, reference being had to the accompanying drawing, forming part thereof, wherein,

Figure 1 is a front view of a textile fabric showing my new design.

Figure 2 is a back view of the textile fabric shown in Figure 1.

The design comprises stripes made up of alternate raised crinkled portions grouped and interspaced as shown.

I claim:

The ornamental design for a textile fabric substantially as shown and described.

E. IRVING HANSON.
